(57) **CLAIM**

The ornamental design for an electric scooter, as shown and described.

DESCRIPTION

FIG. 1 is a perspective view showing top, left and rear sides of an electric scooter.

FIG. 2 is a right side view of the electric scooter of FIG. 1.

FIG. 3 is a left side view of the electric scooter of FIG. 1.

FIG. 4 is a front view of the electric scooter of FIG. 1.

FIG. 5 is a rear view of the electric scooter of FIG. 1.

FIG. 6 is a top view of the electric scooter of FIG. 1; and,

FIG. 7 is a bottom view of the electric scooter of FIG. 1.

Where utilized, the broken lines show portions of the electric scooter that form no part of the claimed design. All dash dot lines are boundary lines and form no part of the claimed design.

1 Claim, 5 Drawing Sheets
